GAME BOARD

Noel Paul Stookey, 70 Bedford St.,
New York, N.Y. 10014

Filed Feb. 14, 1966, Ser. No. 1,022

Term of patent 14 years

(Cl. D34—5)

FIG. 1.

FIG. 2.

FIG. 1 is a perspective view of a gameboard showing my new design; and

FIG. 2 is a rear perspective view thereof with the top raised.

The broken line showing of chess pieces in FIG. 2 is for illustrative purposes only.

My design is characterized by the provision of stepped-down tiers commencing from the four edges of the board and terminating in the four central interior squares, all as shown.

I claim:

The ornamental design for a game board, as shown and described.
